VENTILATING SKYLIGHT

Christian Young, Detroit, Mich.

Application March 26, 1930. Serial No. 438,936

11 Claims. (Cl. 108—16)

This invention relates to skylights and to a roof construction designed to permit ventilation. More particularly, the construction is concerned with a skylight embodying certain features of construction which permits the skylight to be opened for ventilating purposes. In the present case a skylight is shown and described although it must be appreciated that the construction which affords for the ventilation is applicable to roofs other than skylights.

The invention has a number of objects among which is the provision of a construction which can be opened to permit ventilation and yet which effectively keeps out rain, snow or the like. In this regard an element which may be termed a windshield is provided which is mounted so as to protect the vent opening but which may also be bodily actuated so that increased ventilation is obtained. Skylights having openable parts have heretofore been employed. One example is in a gable skylight where opposed parts are hinged on the ridge line. When these are opened air may pass right through the opening, in one side and out the other; the result is that the desired ventilation is not accomplished because there is sufficient movement of air into or out of the underlying building as the outside atmosphere merely passes through the two aligned openings. The present invention contemplates a structure applicable to a ridge of a gable roof, but in which the parts do not hinge upon the ridge line. More specifically, the angle of the ridge is maintained, and two adjacent parts on opposite sides of the ridge may be moved, preferably, on a hinge line located remote from the ridge.

In a general way the structure comprises a pair of sashes rigidly connected to each other in an angular manner at the ridge line of the gable. The structure is hinged at the end of one sash so that the whole can be raised and lowered. The opposite sash has a windshield member designed to protect the opening as the structure is raised. This effectively keeps out the elements. When additional ventilation is required the two window frames or sashes may be further raised to lift the windshield from its protecting position. Thus the movable ventilating parts remain attached on one side of the roof so that air cannot pass directly through the openings but more or less compels air to pass from the outside into the building, or vice versa. The movable parts have a seat upon which they are closed, and in regard to this seat the movable parts have considerable overhanging, which further

aids in keeping out the elements. The invention will be better understood by reference to the accompanying drawings where:

Fig. 1 is a plan view of a roof equipped with three ventilating units, the roof being a skylight 60 construction.

Fig. 2 is a sectional view illustrating the ventilating structure closed.

Fig. 3 is a similar sectional view illustrating the same partly open with the windshield functioning to protect the opening.

Fig. 4 is a similar sectional view illustrating substantially maximum opening.

Fig. 5 is a side elevation of a skylight roof constructed in accordance with the invention. 70

Fig. 6 is an enlarged sectional view taken through the ridge substantially on line 6—6 of Fig. 1.

Fig. 7 is a detail in section illustrating the structural features in and around the lower edge 75 of the movable sash showing the windshield mounted thereon.

Fig. 8 is an enlarged section on line 8—8 of Fig. 1 illustrating the overhang of the movable sash.

Fig. 9 is a sectional view taken substantially on line 9—9 of Fig. 10.

Fig. 10 is a composite sectional and side elevational view of the ventilator operating mechanism.

Fig. 11 is a somewhat diagrammatic view showing the principle of the preferred operating mechanism.

Fig. 12 is a plan view of the structure shown in Fig. 11.

Fig. 13 is an enlarged detail view illustrating the operating parts.

Fig. 14 is an enlarged sectional view taken substantially on line 14—14 of Fig. 12.

Fig. 15 is an enlarged sectional view taken 95 through the sash adjacent the pivot construction.

Fig. 16 is a sectional view taken at right angles to that of Fig. 15.

Fig. 17 is a sectional view substantially on line 17—17 of Fig. 18 looking in the direction of the arrows and also parts other than on the windshield.

Fig. 18 is a view of the windshield.

Fig. 19 is a sectional view taken on line 19—19 of Fig. 18.

A gable roof is shown in Fig. 5, and it is generally indicated at 1 and provided with three movable ventilating units 2. The structure shown is that of a skylight and hereafter this word is used instead of "roof" although it is to be appreciated 110

that roofs other than glazed structures may be included. The roof, as shown, comprises glass panels 3 with astragals or bars 4. By reference now to Fig. 2 it will be noted that the movable parts generally referenced 2 comprise glass panel 5, another glass panel 6 on opposite sides of the ridge 7. These panels are rigid with respect to each other and held in a suitable sash and the whole is pivoted as at 8. The panels 5 are carried by a sash advantageously consisting of an angle strip 10 (Fig. 8) with one leg of the angle depending downwardly, the purpose of which will later appear, and also a suitably shaped sheet metal member 11. At the ridge (Fig. 6) the sashes for the panels 5 and 6 are equipped each with angle members 12 rigidly fixed with respect to each other; in this regard a V shaped insert member 13 may be placed between the angle members 12 and welded thereto. A sheet metal exterior ridge member 14 of proper shape may be slipped over the two upstanding legs of the angle members 12.

There are, preferably, angle members 15 which abut against the lower ends of the panels 3. These parts 15 may be termed "glass stops." It is to be understood that suitable packing for the glass is used where needed in the usual manner familiar to those versed in the skylight art.

The sash, which is movable, is pivotally mounted at 8, on pivot studs 16 carried by angle bars 17 (Fig. 15). These angle irons 17 are supported by the skylight bars, the structure of which is illustrated in Fig. 15, and are positioned substantially at the dividing line between the uppermost series of glass panels 3 and the next lower series of panels. The side angles of the sash 10 are apertured to receive the studs. The bars, which divide the skylight roof, comprise inverted T shaped members 20 over which sheet metal caps 21 are placed.

The bars underlying the ventilating sash carry means upon which the glass sash 5 is adapted to seat. This means may take the form of a sheet metal strip 22 formed around the bar 20, as at 23, extending underneath the cap 21, as at 24, vertically rising therefrom and terminating at its upper edge in a roll or bead 25 (Fig. 8). The glass seats on the roll 25 and there is sufficient resilience in the sheet metal so that it adjusts itself to the glass and forms an effective seal. At the hinged end of the sash there is a similar sheet metal member 26 having a roll or bead 27. At the openable end of the sash is a similar sheet metal member 28 terminating in a roll or bead 29.

Accordingly, it will be seen that two window frames are provided which are angularly disposed with respect to each other with the ridge of the gable roof at the angle; these two frames which are rigid with respect to each other (Fig. 8) are pivotally mounted at one end (Fig. 2) but free at the opposite end; the sash may be raised to the position shown in Fig. 3; it may be further raised to the position shown in Fig. 4.

At the free or openable end of the sash a windshield 30 is provided. This windshield comprises glass panels held in a sash at their upper and lower ends, as illustrated at 31 and 32 (Fig. 7) and at their sides 33 (Fig. 17). These are channels and the windshield is preferably made up in two glass panels placed in position in the channels in three sides and then connected by munnion strips 35 (Fig. 19).

The side channels have an extending wing 36 which carries bar 37 having an angularly disposed end 38 which forms a stop. A rod 40 is carried by the depending legs of the angle

members 10 and the windshield is pivotally mounted on this bar 40, as illustrated at 41.

The lower edge of the windshield slides upon the bar caps and, in fact, seats substantially thereon when the ventilator is closed; for instance in Fig. 2. When the ventilator is raised, the windshield, which is freely pivoted, swings as illustrated in Fig. 3 sliding along the bar caps. When, however, the stops 38 strike the sash further swinging of the windshield is prevented, and upon further opening of the ventilator the windshield is raised, as illustrated in Fig. 4.

With the parts adjusted as shown in Fig. 3, ventilation is provided with the elements effectively kept out. Rain or snow driving against the windshield is prevented from entering the vent opening. Due to the fact that there is considerable overhang of the movable sash, as shown in Fig. 8, rain or snow, except in the event of a severe driving storm, cannot enter the vent opening from the side. Nor can the air easily pass into and out of the open sash without ventilating the building, such as was the case in the structure heretofore used. For example, a stream of air coming in from the left (Figs. 3 or 4) either straight or at an angle, strikes the glass next adjacent the pivot and is deflected downwardly; a stream of air coming from the right, angularly or straight, strikes the glass next adjacent the windshield, and the windshield itself, and is deflected downwardly.

The present invention contemplates also an improved operating mechanism for raising and lowering this ventilating sash. This preferred mechanism comprises a longitudinally reciprocating channel strip 50 arranged to be reciprocated as by means of a gear 51, and having teeth meshing in punched out openings 52 in the channel, and this gear is mounted on a shaft or pipe 53 carrying a pulley or wheel 54 which may be hand operated but which, as is the usual case, is elevated so that it cannot be reached by hand and accordingly may be operated by a chain running thereover. This reciprocating channel is provided with a number of inclined planes, there being preferably one inclined plane for each ventilator. These inclines or inclined planes may be provided by bar stock which may advantageously be half round in cross section (Fig. 10), the inclines being shown in 54 (Fig. 11). The reciprocating channel may be suspended from the roof by hangers 55 provided each with a roller 56 carried upon pin 57 upon which the channel rests. The shaft or pipe 53 may be suspended from hangers 58.

Secured to each ventilator sash is an operating arm 60 having attached thereto a spaced arm 62; these are connected at their ends by a bolt 63, and have a roller 64 mounted on a suitable rivet or bolt 65.

The member 54 is positioned between the roller 64 and the bolt 63. Accordingly, when the channel is shifted the inclines 54 engage their respective rollers 64 and lift the same. In the full line position in Fig. 11 the inclines are shown in a position where the ventilators are closed; the dotted line positions show substantially maximum movement with maximum ventilator lift.

It will be appreciated, of course, that the ventilator can be operated by other means. The particular means shown is advantageous for long buildings wherein there is quite a large number of ventilators to be controlled. Smaller installa-

tions, as for example where there are only two or three ventilators, they may be raised and lowered individually by hand.

Where the lifting bracket 60 attaches to the 5 ventilating sash it passes beyond the bead which seals against the glass; it is necessary, therefore, to provide clearance for this purpose; this is shown in Figs. 7 and 9. Here it will be noted that the metal, which forms the sealing strip, 10 is slotted, as at 70, for the reception of the bracket 60 and the sealing bead on the cut-out portion is depressed and seals against the lower edge of the bracket, as illustrated in Fig. 7.

I claim:

15 1. The combination with a gable roof, a pair of angularly disposed sash members for closing a ventilating opening in the roof, said sash members being angularly disposed and rigid with respect to each other with the ridge line of the 20 roof being located substantially at the angle, means pivotally mounting one sash at its lower end, the lower end of the other sash being free, and means for raising the sashes on said pivot.

25 2. The combination with a gable roof, a pair of angularly disposed sash members for closing a ventilating opening in the roof, said sash members being angularly disposed and rigid with respect to each other with the ridge line of the 30 roof being located substantially at the angle, means pivotally mounting one sash at its lower end, the lower end of the other sash being free, and means for raising the sashes on said pivot, and an additional shield device pivotally attached to the sash opposite to the pivot mounting.

35 3. A ventilating skylight of gable construction comprising, a gable roof formation having a vent opening, a pair of window sashes rigidly connected to each other at the ridge line of the gable roof, means pivotally mounting one sash at its 40 lower end to the roof, and means for raising both sashes on said pivot.

45 4. A ventilating skylight of gable construction comprising, a gable roof formation having a vent opening, a pair of window sashes rigidly connected to each other at the ridge line of the gable roof, means pivotally mounting one sash at its lower end to the roof, the other sash being free, and means for raising both sashes on said 50 pivot, and a shield device carried by one sash opposite the pivot mounting.

55 5. A skylight construction comprising a roof formation of gable type having a vent opening near the top, a window sash covering the opening on one side of the gable, means pivotally mounting it below the opening, another window sash covering the opening on the opposite side of the ridge line, means rigidly connecting these 60 two sash members at the ridge line with said connection being rigid, means for raising the two sashes on said pivot mounting, and a shield member pivotally carried by the lower end of one sash.

65 6. In a ventilating skylight, a gable roof construction having a vent opening in the top, a pair of sashes angularly disposed and rigidly connected along the ridge line, means pivotally connecting the lower end of one sash to the roof, the lower end of the other sash being free, a shield

pivotedly connected to the free end of the one sash, means for raising the sashes on the pivot, said shield pivoting on its mounting in this action and maintaining contact with the roof.

7. In a ventilating skylight, a gable roof construction having a vent opening in the top, a pair of sashes angularly disposed and rigidly connected along the ridge line, means pivotally connecting the lower end of one sash to the roof, the lower end of the other sash being free, a shield pivotedly connected to the free end of the one sash, means for raising the sashes on the pivot, said shield pivoting on its mounting in this action and maintaining contact with the roof, and stop means for limiting the pivot action of the shield whereby upon further raising of the sashes on their pivot they bodily raise the shield from the roof.

8. In a ventilating skylight, a gable roof construction having a vent opening in the top, a pair of sashes angularly disposed and rigidly connected along the ridge line, means pivotally connecting the lower end of one sash to the roof, the lower end of the other sash being free, a shield pivotedly connected to the free end of the one sash, means for raising the sashes on the pivot, said shield pivoting on its mounting in this action and maintaining contact with the roof, and stop means for limiting the pivot action of the shield whereby upon further raising of the sashes on their pivot they bodily raise the shield from the roof, said sash members having an overhang as regards the opening and said overhang and shield serving to protect the opening from the elements.

9. A ventilating skylight comprising a gable roof having transversely extending bars raised from the plane of the roof, a pair of sashes rigidly connected and angularly disposed at the ridge line of the roof, means pivotally mounting one sash at its lower edge to the roof, a pivotally mounted shield at the lower edge of the other sash, said shield lying on at least two of the bars, means for raising two sashes on the said pivot, said shield pivoting on its mounting in this action and sliding on the bars.

10. A ventilating skylight comprising a skylight of gable construction having vent openings in its top, transverse bars in the roof construction, a pair of sashes rigidly connected and angularly disposed at the ridge line of the roof, means movably mounting the same, means for raising and lowering the sash members, said sash members having an overhang as regards the bars to aid in keeping out the elements.

11. A ventilating skylight comprising a skylight of gable construction having vent openings in its top, transverse bars in the roof construction, a pair of sashes rigidly connected and angularly disposed at the ridge line of the roof, means movably mounting the same, means for raising and lowering the sash members, said sash members having an overhang as regards the bars to aid in keeping out the elements, and means depending from the edges of the sash members for cooperating with the bars to keep the elements out of the vent openings.
